UNITED STATES PATENT OFFICE

1,953,987

ADVERTISING DISPLAY DEVICE

Charles Roberts and John J. Vertrees, New York,
N. Y.

Application May 16, 1933, Serial No. 671,326

13 Claims. (Cl. 40—36)

This invention relates to a device for displaying advertising cards of conventional size and composition. We are aware of the prior art disclosing devices which display advertising cards at the front and back of the machine and in which a rotating friction drum at one end of the machine reverses the card after it is displayed in the front of the machine so that it may again be displayed at the rear window of the machine. However, all machines hitherto of this general type, complicate the advertising card as displayed in the machine and militate against the commercial value of the device because all these prior mechanisms require in some form, an attachment to the card which is glued on, crimped on or otherwise attached, or, on the other hand, the prior art shows cards which must have a cut-out or actual insertion of some form in the card material in order for the card to properly pass through its cycle of display in co-ordination with the mechanism of the machine.

One of the main objects of this invention, therefore, is to utilize in our display device strictly standard commercial advertising cards without any addenda whatever thereto. It is to be further noted that two of these cards are inserted in each holder element in the magazine and that they are placed loosely in the same, back to back, and entirely free one from the other. A further object is to provide means to keep the loosely held cards in perfect alignment, edge to edge, as they pass around the carrier mechanism to complete their card cycle, otherwise after several cycles through the machine in their loosely held and sustained condition they would be badly out of alignment and destroy their effectiveness of display as and when shown in the display windows of the machine.

A further object of our invention is to provide simple and positive means to feed the two cards, thus positioned, back to back, into the friction drum from the magazine, and furthermore to positively carry them away from the drum to their proper sustaining grooves in the transverse positioned magazine, and it is to be further noted that this same feeding mechanism keeps the cards automatically in an aligned position in respect to the one and the other after their reversal.

With the above and other objects in view as will appear as the nature of the invention is thoroughly understood, the same consisting in the novel construction and combination and arrangement of parts as may be hereinafter fully described and claimed, we proceed to the detailed description of our invention.

In the accompanying drawings forming part of this specification, it is understood that the drawings will serve to show a representative embodiment of our invention in which like characters of reference indicate corresponding parts.

Fig. 1 is an enlarged plan view, partly in section, of our invention showing the co-ordination of the magazine and the feeding and ejecting card mechanism therefor.

Fig. 2 is a side elevation, also partly in section, showing the co-ordinated mechanism used to operate the card kickers into and out of the magazine, and is a section taken on the line A—A in Fig. 1.

Fig. 3 is an end elevation of the machine taken on line D—D, Fig. 1.

Fig. 4 is a fragmentary end section taken on line B—B, Fig. 1.

Fig. 5 is an end sectional view taken on line C—C, Fig. 2, showing the Geneva-stop-movement which controls in unison the top and bottom transverse magazine holders.

Fig. 6 is a fragmentary plan view showing the two cards placed back to back passing around the reversal drum and about to be positively carried on to the magazine by the transfer mechanism. The rear end of the two cards as they leave the drum are shown out of alignment caused by their occupying different length of radii as they pass around the periphery of the rotating friction drum.

Referring more particularly to the drawings, we show bed plates 1 and 2, see Fig. 2, which support in proper journals the four shafts, viz; 3—4—5 and 6. The shafts 3 and 4 are connected by a perforated endless belt 7 engaging in sprockets 8 and 9 respectively, mounted on shafts 3 and 4. The four shafts are thus synchronized and will turn one-sixth of a revolution for each cycle of the machine, as will be explained hereafter in the specifications. The main frames, 10 and 11, are secured to bed plates 1 and 2 which support a motor shaft 12 actuated by any motive source that may be desirable to use. The shaft 12 carries in its innermost end a bevel gear 13 meshing with another miter gear 14 secured on vertical shaft 15 on which the drum 16 is likewise secured. Drum 16 revolves continuously during the machine's operation.

Around the drum 16 are one or more half-moon belts 17, one in an upper position and one in a lower position thereon (not shown) guided by three vertical idlers 18—19 and 20 and a fourth idler 21 mounted between arms 22 of a

110

yoke mounted on shaft 23. Spring 24, by means of a bell-crank arm 22a, integral with arm 22, gives the two belts 17 a constant tension and insures their friction contact with the drum 16, as is clearly shown in Fig. 1. The shafts 3—4—5—6 each carry two sprockets 3a—3b; 4a—4b; 5a—5b and 6a—6b respectively. On these sprockets are mounted chains 25—25a and 26—26a. Between the two top chains 25 and 10 25a, see Figs. 2 and 3, channels 27 are suitably secured thereto with their longitudinal axis parallel to the major axis of the machine.

Likewise, at the bottom, channels 28 are also secured in like relation. The sprockets are so 15 keyed to their respective shafts that the upper channels 27 are in exactly vertical alignment with the lower channels 28 so that the advertising cards, as indicated by 29, can be freely and easily inserted therein without any attachments 20 whatsoever and may be kept in a substantially vertical position in respect to the front and rear windows, as is indicated in 30 and 31. In this manner, the cards are properly spaced and inserted two in each channel, back to back, and 25 as the machine operates, they are progressively advanced by the magazine which is composed of the upper and lower series of card sustaining channels, and in this manner progressively recede from the rear window and move towards 30 the front window in predetermined synchronism with the entire machine's mechanism, as will be now fully explained.

A card kicker arm 32, fulcrumed at the top of the machine by pin 32a and actuated by link 33, the lower end of which is guided by its slotted end 33a, a roller 34 riding on cam 35 which is secured to shaft 36 gives the initial motion to the two cards contained in the upper and lower synchronized channels nearest to the front window 40 30. By pushing the cards, which contact with the pin 32b on the end of kicker arm 32, as is clearly seen in Fig. 1. The pin 32b thus pushes off the card from the channels past the guides 37 and between the two friction belts 17 and the drum 16. It is to be noted that the kicker arm 32 passes through the opening 52a in partition 45 11 and the spokes on gear 52 escape contact with the kicker arm due to predetermined meshing of the gear together with its relative slow speed. Arm 32 in Fig. 4 is shown passing through the opening 52a.

In like manner, another card pusher element 55 38, see Fig. 2, which extends across the magazine and is guided in frames 10 and 11 and terminates as is shown in Fig. 6 in a bent hook member 38a and is actuated by bell-crank arm 39 and link 40 which likewise contains the guide slot 40b riding on shaft 36 and is actuated by cam 42, suitably secured to shaft 36. Cam 42 is so timed in respect 60 to the cycle of the machine that hook 38a is in a forward position, see Fig. 6, and out of contact with the cards as they are in transit around the friction drum 16 but hook 38a moves backward by the setting of the cam 42 at the proper moment as and when the cards clear from the drum 16 so as to push the rearmost edges of the two cards on to the rearmost magazine channels 27 and 28 which are now empty and ready to receive the cards in question.

70 It is to be noted that the hook 38a contacting with the respective rear edges of the cards, now loosely carried and sustained by guides 50 and the channel members 27 and 28, are in this manner necessarily re-aligned, one in respect to the 75 other, after they leave the friction drum as they

are pushed into place on to the sustaining magazine channels.

Referring to Fig. 5, the main drive shaft 12 has a pinion 51 meshing with the large gear 52 which turns on a bearing 53 sustained by frame member 11, see Fig. 2. A small gear 54, fastened securely to the rear of gear 52 meshes with the idler gear 55 which in turn engages the gear 56, to which gear is secured on arm member 57 with a cross pin 58 inserted in its outermost extremity. This pin in its relatively slow rotation as reduced in revolutions per minute, by the above mentioned gear train periodically meshes with a recess 58 on disk 59 which is secured to shaft 6, on which is carried sprocket 6a and on which chain 26a engages. In this manner, through a conventional form of Geneva-stop-motion comprising disk 59 and the arm 57 with its engaging pin 58, an intermittent motion of the proper sequence and timing is given to the magazine with its transverse upper and lower card supporting channel members. The magazine is stationary as and when the kicker 32 and the pusher 38, respectively, push off and pull on the cards from and to the magazine, but moves forward in proper degree as and when the two cards have been deposited on to the rear-most channel members of the magazine by pusher 38. The lever 60 with its locking roller 62 and the spring 61 insures the magazine's mechanism remaining stationary until the slowly rotating arm dictates its predetermined movement, as above described.

From the foregoing description, the operation of our invention is very readily seen. The magazine being filled with cards, two placed in each corresponding upper and lower channels in the magazine, the most rearward channel being kept purposely empty of cards, the machine is started into motion. The kicker 32 pushes the cards in the frontmost channels forward in friction contact with the drum 16 wherein the cards are engaged between the belts 17 and the drum 16, and as and when the cards leave the friction contact of the same, the pusher arm 38a, Fig. 6, pushes them forward re-aligning their respective rear-most edges and carrying the cards in proper position on to the empty top and bottom rearmost channels of the magazine. The magazine's mechanism now comes into action advancing the cards in all their respective upper and lower channel sustaining positions forward toward the front window to the extent of one channel segment on the conveying sprockets. The machine has now arrived in its operation to its initial position previously described, and this cycle is again repeated.

This machine operates with great smoothness. The movements are gradual in their acceleration and deceleration and cause no injury to the unprotected loosely sustained advertising cards. Great emphasis is placed by us on the fact that this machine displays cards as are now supplied by the advertising trade for stationary advertising, and in this manner, its commercial value is greatly enhanced for the reason clearly brought out in the specifications and in contrast to the prior art. It is furthermore pointed out that a standard commercial card, if printed on both sides with advertising matter, can be put into our machine without attachment or addenda of any nature and will function perfectly in the machine just as the two separate cards placed back to back in each magazine compartment. Finally, no groups of cards in any magazine division or single

card, if placed therein, ever contacts with another group of cards or card during their or its complete cycle through the machine. This valuable feature reduces wear by chafing contact of 5 the paper display placards or cards.

What we claim and desire to secure by United States Patent is defined by the following claims:

1. In a card display device having a front window and a rear window, comprising an endless 10 chain card magazine and means to loosely sustain the cards therein and means to advance said sustaining means in said magazine from said rear window towards said front window, means at one end of said magazine to reverse said cards and 15 pushing means to slide said cards out of the frontmost of said card sustaining means into said card reversing means and means to convey said cards from said reversing means on to the rearmost of said card sustaining means in said 20 magazine.

2. In a display device, the combination of a plurality of flexible placards in groups of two, all of said placards being unattached and independently supported therein and means for displaying said placards and means for reversing said placards after display and means for re-aligning each placard in respect to the other in each group after said reversal.

3. In a display device, the combination of a 30 plurality of flexible placards arranged in groups of two, back to back, both of the placards in said placard groups being entirely free, one from the other, and unattached in said device, means for displaying said placards, means for reversing said placards and means for re-displaying said placards.

4. In a display device, comprising an endless 40 chain magazine with corresponding upper and lower supports, each of said upper and lower supports jointly sustaining two flexible placards loosely and independently placed therein, means for reversing the said two placards simultaneously and means for re-aligning said two placards, one with the other, after said reversal.

5. In a display device, comprising an endless 45 chain magazine with corresponding upper and lower movable supports, said upper and lower supports jointly containing two flexible placards placed back to back, each of said placards resting 50 entirely unattached therein and independent, one from the other, means for displaying said placards, means for reversing the said two placards simultaneously, and means for re-displaying said placards.

6. In a display device having a front window 55 and a rear window, comprising an endless chain with corresponding upper and lower supports, each of said upper and lower supports jointly containing two flexible placards placed back 60 therein and entirely free, one from the other, and sustained unattached therein, means for displaying one of said placards in the said front window and means for reversing the said two placards.

ards and means for displaying the same placard at the rear window.

7. In a display device having a front window and a rear window, the combination of a plurality of flexible placards sustained in groups of two, all of said placards being unattached and independently supported therein, means for reversing said placards after displaying at said front window and automatic means for re-aligning each group of placards one in respect to the other after said reversal.

8. In a display device having a front window and a rear window, the combination of a plurality of flexible placards, in groups of two, all of said placards being unattached and independently supported therein, means for displaying one of the placards in each group at the front window of said device and means for reversing each group of placards after said display and means for displaying the same placard in each group at the rear window in said device.

9. In a display device, comprising an endless 100 chain magazine with corresponding upper and lower supports, each of said upper and lower supports jointly containing two flexible placards placed back to back and sustained therein entirely unattached thereto and independent, one from the other, means for displaying one of said placards in each group and means for simultaneously reversing each group of placards and 105 means for displaying again the same placard in each group.

10. In a display device, the combination of a plurality of flexible placards supported therein unattached and in groups of two, back to back, 110 and means for displaying said placards and means for reversing said placard groups after display.

11. In a display device, the combination of a 115 plurality of flexible placards arranged in groups of two, back to back, both of the placards in said placard groups being loosely sustained and unattached, one to the other, means for displaying said placards and means for reversing said placards.

12. In a display device, the combination of a plurality of flexible placards, a display window therefor, means to pass said placards serially before said display window and conveyor, carrier and reversal means therefor and means to keep 125 each placard entirely apart from any other placard while completing its cycle through said device.

13. In a display device, the combination of a plurality of flexible placards, a display window 130 therefor, means to pass a plurality of said placards in groups of two placed back to back in front of said window, conveyor, carrier and reversal means therefor and means to retain each group of placards entirely apart from any other 135 group while completing its cycle through said device.
